VENTILATING SYSTEM

George S. Dauphinee, Brooklyn, N. Y., assignor
to William B. Connor, New York, N. Y.

Application September 8, 1943, Serial No. 501,510

6 Claims. (Cl. 98—40)

1

The invention relates to improvements in ventilating systems and more particularly to a method of diffusing air or gas within a ventilated enclosure as well as to an improved air or gas diffuser.

The ventilating systems to which the invention is particularly applicable comprises a series of diffusers arranged along the ceiling of the enclosure. The rate of air supplied through these diffusers to the enclosure is largely governed by the rate of internal heat generation and the rate of heat generation from tools, machines and the like in manufacturing buildings generally is very high. It is therefore quite a problem to introduce air into these enclosures at a sufficiently high rate to maintain comfortable conditions with respect to the temperature without the creation of objectionable drafts.

Modern building construction has become quite standardized and most of these standard constructions include close column spacing and low ceilings which further tend to complicate the problem of draftless ventilation. Usually the columns in these standard constructions are spaced 20 feet apart in each direction and the ceiling height varies between 10 and 12 feet. From a construction standpoint as well as from a standpoint of symmetry, it is most practical to locate the inlets in the center of the bays or squares defined by the column centerlines.

The pattern of air distribution obtained from the diffusers arranged in this manner shows radial flow areas along the underside of the ceiling where the primary air or supply air merges with the secondary air or aspirated air, which is drawn vertically upward from the room, and down flow areas at the corners of the bays, thereby establishing a continuous circulatory movement throughout the room.

Now, the maximum amount of cooling air introduced per square foot of floor area with freedom of objectionable drafts reaches a definite limit for constructions of the aforesaid dimensions and drafts in working spaces have proved a serious factor upon the efficiency of the plant and its workers. Usually air currents having a flow rate of over 50 feet per minute are considered objectionable drafts. Although ventilating engineers are fully aware of this limitation upon the supply of cooling air, modern conditions still demand an ever increasing rate of air supply to these buildings. For these reasons, the diffusers must be designed and arranged to perform to their utmost capacity limit.

It is of course also important to bring about as

2

complete a temperature equalization between the supply air and the room air as possible. Naturally, if the temperature equalization is incomplete, the drafty air will be colder than the room air, thus causing the workers still greater discomfort. However, even if the diffusers along the ceiling should perform 100% as an equalizing or mixing device, it still may not accomplish a uniform rate of air circulation throughout the working space, thus causing drafts in portions of the working area.

In order to increase the rate of air exchange, it has been proposed to increase the energy of the supply stream but the radial flow areas will then overlap and as the velocity at impact is much more than 50 feet per minute, objectionable downdrafts will occur at the points of overlap. Furthermore, as the velocity of the stream is increased, the downward flow areas at the corners of the squares or bays naturally will diminish. This obviously will further increase the high velocity of the downdraft.

It is therefore among the objects of the present invention to eliminate or minimize these objectionable drafts.

Another object is to increase the rate of air change within the ventilated enclosure with freedom of objectionable drafts.

A further object is to effect a more rapid mixing of the supply air with the room air resulting in more rapid and complete temperature equalization.

Still another object is to increase the downward flow areas and maintain a uniform and continuous circulation of air throughout the enclosure.

Other objects and advantages inherent in the invention will become apparent from the following description taken in conjunction with the accompanying drawing which shows by way of example an embodiment of the inventive idea.

In the drawing:

Figure 1 is a fragmentary schematic view of the pattern of air distribution within an enclosure obtained from the conventional diffusers.

Figure 2 is a fragmentary schematic plan view of the horizontal air distribution along the underside of the ceiling according to one form of the invention.

Figure 3 is a fragmentary sectional view of a diffuser according to the invention set into the ceiling of the enclosure.

Figure 4 is a bottom plan view of the diffuser shown in Figure 3.

Figure 5 is a plan view of one of the sectorizing bars according to the invention, and

Figure 6 is a side view thereof.

Through the drawing the same reference characters serve to indicate the same or analogous parts.

Referring in greater detail to Figures 1 and 2, the enclosure shown therein embodies a ceiling A, a floor line B and walls C. The center columns E as well as the wall columns F are spaced an equal distance apart and for the purpose of this description the standard spacing of 20 feet has been selected. The diffusers G are set into the ceiling A and connected to the supply ducts I and are located in the center of the squares or bays defined by the column centerlines. (See Figure 2.)

The diffused or deflected air in areas in accordance with present day practice are in the form of complete circles or discs. Accordingly great care has to be taken to prevent these discs from unduly overlapping or colliding by choosing the energy factors (volume and exit velocity), of the supply stream so that this energy will be well spent at the points of contact. Radial flow velocities at point of contact over 50 feet per minute will generally cause objectionable drafts. This flow area is of disc formation, relatively thin and hugging the under surface of the ceiling. This general form of air flow is common to all diffusers designed for low ceiling surface. In high buildings it might of course be desirable to diffuse the air more downwards.

It will be seen from Figure 1 that the primary or diffused air stream as it leaves the diffuser is augmented by aspirating the layer of room air directly below the discharge disc throughout its course. Thus, the direction of the air currents or air movements directly below the discharge disc is vertically upward over the full area of the disc and downward at the corners of the squares or bays. In this manner a continuous circulatory movement is established throughout the enclosure.

The intensity of the upward movement is maximum at the origin of the discharge stream and gradually diminishes to zero at the outer circumference of the disc. Taking the proportions indicated it will be seen that the upward flow area is 100π or 314 square feet. Accordingly, the remaining area of the square providing for the downward flow of the entire stream as augmented by the aspirated room air is only $400 - 314 = 86$ square feet. Therefore, the velocity of the downward flow is many times greater than the velocity of the general upward direction.

Now, if the energy factor of the stream is increased ($mass \times velocity$) the discs will overlap and the downward flow area will become still smaller and consequently the velocity of the downward flow will be still further increased resulting in highly objectionable drafts. Downward drafts will also occur where the discs overlap as the velocity at impact will now be greater than 50 feet per minute. The foregoing explanations are given for the purpose of illustrating the limitations upon the rate of air supply to standard building constructions. It might be suggested to increase the mass and lower the velocity and still maintain the same energy factor (mv), but this does not appear to help the effective draft condition as the mixing effect or temperature equalization diminishes with an increase of M within the limited throw space, as the augmentation rate depends on the area of contact between the surface of the discharge stream and the room

space. Therefore, by increasing the volume or mass of the initial stream and confining it to the 10 foot throw, the percentage of possible temperature equalization will be decreased as compared with the lower mass or volume.

The objects of the invention are accomplished by dividing the radial flow areas or discs into a series of sectors as shown in Figure 2 of the drawing. In each alternate sector *a*, the original or conventional radial flow is maintained as indicated by the broken line whereas in sector *b* eddies prevail producing a combination of upward and downward currents, having a general radial drift outward and downward. The depth of this area is therefore much greater than that of area *a*. Hereafter area *b* will be referred to as the turbulent flow area or sector in contradistinction to area *a* which will be referred to as the radial flow area or sector. In some instances it has been found advantageous to stagger the sectors of adjoining radial flow areas or discs so that un-like sectors oppose each other along the common centerline of the discs. In this manner downdrafts are avoided at the points of overlap. In other words, the velocity of the discharge streams may be increased without the harmful effect of the overlap in the conventional installations.

Again, in the turbulent sectors, especially throughout the outer areas, the balance between the forces promoting radial flow become less than those promoting downward flow. Accordingly, downward flow will take place in these outer areas thereby relieving the tendency for high velocity at the corners of the bays.

It has been found that the sectorization of the radial flow areas increases the mixing effect and the resultant temperature equalization within the limited space. The number of sectors may vary. Although eight forced flow sectors and eight turbulent sectors are shown in the drawing, as few as four sectors of each may be used where draft conditions are less accentuated. Conversely, the number of sectors may be increased when the conditions so require.

Referring in detail to Figures 3 and 4, the diffuser employed in connection with the invention comprises a casing or dome 10 having a neck portion for connection to the supply duct I. The casing 10 is preferably provided with an annular deflector surface 12, against which the supply stream will impinge so as to be slightly deflected thereby, and a dished rim or bead portion 13 engaging the under surface of the ceiling.

In connection with the reference to deflector surface 12 above, it might be pointed out that under normal operating conditions the extent of downward deflection produced by part 12 does not materially change the direct radial disc formation along the ceiling as indicated in Figure 1 but merely retards contact of the stream with the ceiling to a point where the velocity is decreased below that sufficient to throw out dust particles and to cause smudging of the ceiling surface. The effect of the ceiling on flush set diffusers to draw the stream upward is so great that the entire air volume must be initially deflected downward as much as 45 deg. to prevent it producing a low pressure area at the ceiling surface sufficient to draw itself upward.

The inner assembly of the diffuser comprises one or more deflector members 14 and 15 which are spaced from the casing 10 and from one another to define discharge passages 16 and 17 therebetween.

The division or sectorization of the radial flow

areas or discs is accomplished by means of the clips or bars 18 which are positioned about the extreme outer end of the discharge passage 16 across the discharge stream. It is desirable to place these bars or clips as near the outer end of the passage as possible. If placed upward in the passage the divided stream will merge again. For best results, the bars should curve outward and bulge slightly downward. Furthermore even though the width of the blanking clips 18 is not critical to the invention, it should be understood that they must possess sufficient width so as to blank off such portion of the discharge area as to divide the discharge stream into alternate forced flow sectors and turbulent sectors. Thus it has been found that the blanking clips 18 should be at least so wide that they blank off about 5% of the area of the discharge opening. Beyond this lower limit, the width may vary depending upon the number of sectors desired and the particular conditions to be met.

The bars 18 may be so designed that they may be snapped into place intermediate the deflector surface 12 and the bead 21 of the deflector member 14. For the latter purpose, the bars are provided with a hook 22 at one end which easily may be bent about the bead 21. In this manner, the position of the bars about the discharge opening may be easily changed at will. This adjustable feature is important for example where large or bulky machinery is changed to a new position within the area served after the installations of the diffusers and which might alter the pattern of air distributions and set up drafts. By adjusting these bars, these conditions can be easily remedied.

It has also been found that when the diffuser has two or more discharge passages, the sectorization is effective if these bars 18 are placed in the main or upper passage only, as the air from the lower passages has a tendency to be drawn upwards to merge with the main stream and, when the upper stream is sectorized, the lower stream or streams will be to a large extent divided and merge with the sector in which the radial flow is maintained. In some instances, the lower discharge passes may be eliminated entirely.

It will be understood that this disclosure is given by way of example and not by way of limitation. On the other hand the invention may lend itself to a variety of expressions within the scope of the appended claims.

What is claimed is:

1. An air or gas diffuser comprising a casing for connection to a supply duct and a deflector member spaced with respect to said casing to define a tubular discharge passage therebetween, means mounted at the outlet opening of said discharge passage for blanking off a portion of said outlet opening and prevent discharge through said portion, said means having a flat surface normal to the discharge stream and such surface having at least such a width that said blanked off portion will not be less than 5% of the area of said outlet opening, whereby the discharge stream will be divided into alternate forced directional flow areas and turbulent areas.

2. An air or gas diffuser comprising a casing for connection to a supply duct and a deflector member spaced with respect to said casing to define a tubular discharge passage therebetween, and means mounted at spaced intervals transversely across the outlet opening of said discharge passage for blanking off a portion of said

outlet opening and prevent discharge through said passage, said means having a flat surface normal to the discharge stream and said surface having at least such width that said blanked off portion will be not less than 5% of the area of said outlet opening, whereby the discharge stream will be divided into alternate forced directional flow areas and turbulent areas.

3. An air or gas diffuser comprising a casing for connection to a supply duct and a deflector member spaced with respect to said casing to define an annular discharge passage therebetween, means mounted across the outlet opening of said annular discharge passage for blanking off a portion of said outlet opening and prevent discharge through said passage, said means having a flat surface normal to the discharge stream and said surface having at least such width that said blanked off portion will be not less than 5% of the area of said outlet opening, whereby the discharge stream will be divided into alternate forced directional flow areas and turbulent areas.

4. An air or gas diffuser comprising a cone-shaped casing for connection to a supply duct and a deflector member spaced with relation to said casing to define an annular discharge passage therebetween, and a plurality of outwardly and downwardly curved blanking members positioned intermediate the outer ends of said casing and said deflector member and extending below the outlet opening of said discharge passage at spaced intervals about said outlet opening for blanking off a portion of said outlet opening and prevent discharge through said portion, said blanking members having a flat surface normal to the discharge stream and said surface having at least such width that said blanked off portion will not be less than 5% of the area of said outlet opening, whereby the discharge stream will be divided into alternate forced directional flow areas.

5. In a ventilating system for a room or similar enclosure comprising a plurality of diffusers each connected to a supply duct and spaced regularly along the ceiling of said enclosure, each of said diffusers comprising a relatively spaced casing and a deflector member defining a tubular discharge passage therebetween, means mounted at the outlet opening of said discharge passage in each of said diffusers for blanking off a portion of said outlet opening and prevent discharge through said portion, said blanking means having a flat surface normal to the discharge stream and said surface having at least such width that said blanked off portion will be not less than 5% of the areas of said outlet opening, whereby the discharge stream will be divided into alternate forced directional flow areas and turbulent areas, said blanking means being so arranged that the turbulent areas of adjoining diffusers will oppose the forced flow sector on the common centerline of said radial flow areas.

6. An air or gas diffuser for connection to a supply duct, said diffuser having an annular discharge passage for diffusing the supply stream radially, means mounted transversely across the outlet opening of said discharge passage and extending beyond said outlet opening for blanking off a portion of said outlet opening and prevent discharge through said portion, said means having a flat surface normal to the discharge stream and said surface having at least such width that said blanked off portion will be not less than 5% of the area of said outlet opening, whereby the discharge stream will be divided into

alternate forced directional flow areas and turbulent areas.
